UNITED STATES PATENT OFFICE

WILLIAM T. HENRY, OF HOUSTON, TEXAS

INDICATING DEVICE

Application filed September 25, 1928. Serial No. 308,276.

This invention relates to new and useful improvements in an indicating device.

One object of the invention is to provide an indicating device of the character described which has been specially designed for attachment to the instrument board of a motor vehicle for the purpose of indicating to the driver when the lubricating oil should be drained from the motor and fresh oil supplied thereto.

Another object of the invention is to provide a device of the character described which is of simple construction and may be cheaply produced and which is very efficient for the purpose indicated and for other similar purposes.

With the above and other objects in view the invention has particular relation to certain novel features of construction operation and arrangement of parts, an example of which is given in this specification and illustrated in the accompanying drawings wherein

Figure 1 shows a front elevation of the device partly broken away, and

Figure 2 shows an edge view thereof.

Referring now more particularly to the drawings, wherein like numerals of reference designate similar parts in each of the figures the numerals 3 and 5 designate concentric circular plates, one of which is provided with the marginal fingers 4, adapted to be bent over the margin of the other plate to hold the plates in assembled relation, thus forming a casing. Between the plates are the concentric rings 6, 7, 8, 9 and 10. These rings are preferably formed of celluloid or other light durable material, and each ring has the numerals from zero to nine, spaced apart therearound. The plates are held spaced apart by the inner and outer spacer rings 14, 15 so that the rings 6 to 10 will not bind to such an extent that they cannot be rotated. The front plate 5 has a radial slot 13, cut therethrough, through which the numerals on the rings may be exposed and on each side of each numeral the rings are provided with small pin holes 10'. An ordinary pin or other similar instrument may be inserted into one of the holes 10' to turn the corresponding ring. If desired, a pin as 11 may be carried in the side pocket 12.

The device may be secured in place on the instrument board by means of a suitable bolt or set screw passed through the central opening 16 and secured to the instrument board.

When the oil is replenished in the motor, or when the vehicle is lubricated the rings 6 to 10 may be so adjusted as to reveal through the slot 13 the mileage at which the lubricant should next be replenished and when the speedometer indicates the mileage revealed through the slot 13 the driver will be apprised of the fact that fresh lubricant should be again supplied.

While I have shown what I now consider to be the preferred form of the invention it is obvious that mechanical changes may be made therein and equivalents substituted for the parts shown and I reserve the right to make such changes and substitutions as may be found desirable within the principle of the invention.

What I claim is:—

1. A device of the character described comprising concentric plates, inner and outer spacers between said plates, means on the margin of one plate and engaged over the margin of the other plate to clamp the plates against said spacers, one of said plates having a radial slot, a plurality of concentric rings, one within the other, said rings being located between said spacers and being independently rotatable, said rings having numerals to be exposed through said slot.

2. A device of the character described comprising concentric plates, inner and outer spacers between said plates, means on the margin of one plate and engaged over the margin of the other plate to clamp the plates against said spacers, one of said plates having a radial slot, a plurality of concentric rings, one within the other, said rings being located between said spacers and being independently rotatable, said rings having numerals to be exposed through said slot, a side pocket carried by the device, an actuating pin therein engageable with said rings separately and through which the rings may be independently rotated.

3. A device of the character described comprising concentric plates, inner and outer

spacers between said plates, means on the margin of one plate and engaged over the margin of the other plate to clamp said plates and spacers together, one of said plates having a radial cut-away portion, a plurality of concentric rings one within the other, said rings being located between said spacers and being independently rotatable, said rings having numerals arranged to be exposed successively through said cut-away portion, as the rings are rotated.

4. A device of the character described comprising concentric plates secured together in spaced relation, one of said plates having a radial cut-away portion, a plurality of concentric rings one within the other and having numerals to be exposed through said cut-away portion as the rings are rotated, a side pocket carried by the device, an actuating pin therein engageable with said rings separately and through which the rings may be independently rotated.

In testimony whereof I have signed my name to this specification.

25 WILLIAM T. HENRY.
